(57) **CLAIM**

The ornamental design for a packaging, as shown and described.

DESCRIPTION

FIG. 1 is a front, left side, top perspective view of a first embodiment of packaging showing my new design;

FIG. 2 is a rear, right side, bottom perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is a front, left side, top perspective view of a second embodiment of the packaging;

FIG. 10 is a rear, right side, bottom perspective view thereof;

FIG. 11 is a front view thereof;

FIG. 12 is a rear view thereof;

FIG. 13 is a right side view thereof;

FIG. 14 is a left side view thereof;

FIG. 15 is a top view thereof; and,

FIG. 16 is a bottom view thereof.

The vertical broken lines along the right side of the packaging in the drawings illustrate portions of the packaging that form no part of the claimed design. The additional broken lines in the second embodiment are for the purpose of illustrating portions of the packaging with a symbolic break in its height. The appearance of any portion of the article between the break lines forms no part of the claimed design.
